UNITED STATES PATENT OFFICE.

MAX ARNOLD, OF NEW YORK, N. Y., ASSIGNOR TO HERMAN SCHEUER'S SON & CO., OF NEW YORK, N. Y., A COPARTNERSHIP COMPOSED OF JACOB H. SCHEUER AND HENRY LICHTENSTEIN.

DESIGN FOR A LADY'S HAND BAG.

Application filed September 7, 1927. Serial No. 23,318. Term of patent 3½ years.

To all whom it may concern:

Be it known that I, MAX ARNOLD, a citizen of the United States, and a resident of the city of New York, borough of the Bronx, in the county of Bronx and State of New York, have invented a new, original, and ornamental Design for a Lady's Hand Bag, of which the following is a specification, reference being had to the accompanying drawing forming a part thereof, in which—

Figure 1 is a perspective view of a lady's hand bag, showing my new design; and Fig. 2 is a side elevation of the bag showing my new design.

I claim:

The ornamental design for a lady's hand bag, substantially as shown.

MAX ARNOLD.
